UNITED STATES PATENT OFFICE.

DANIEL J. MCOSKER AND OWEN F. GARVEY, OF PROVIDENCE, RHODE ISLAND,
ASSIGNORS OF ONE-THIRD TO GEORGE E. PALMER, OF CRANSTON, RHODE
ISLAND.

SAFETY-COCK FOR GAS OR LIQUIDS.

SPECIFICATION forming part of Letters Patent No. 623,331, dated April 18, 1899.

Application filed March 7, 1898. Serial No. 672,878. (No model.)

To all whom it may concern:

Be it known that we, DANIEL J. MCOSKER and OWEN F. GARVEY, of Providence, in the State of Rhode Island, have made certain new and useful Improvements in Safety-Cocks for Gas or Liquids; and we do hereby declare that the following specification, taken in connection with the drawings making a part of the same, is a full, clear, and exact description thereof.

Figure 1 is a central vertical section through the entire device, the valve being in the closed position. Fig. 2 is a similar view with the valve in the open position. Fig. 3 is a top plan view of the key-guide with the key in place, illustrating the co-operative relation between the key-lugs and the stop-lugs upon the guide. Fig. 4 is a detail perspective view of the valve. Fig. 5 is a similar view of the guide. Fig. 6 is a detail view of the spring M.

Referring to the letters of reference on the drawings, A indicates the rear end of a gas or other fixture, which is attached, as usual, to the gas or other pipe.

B indicates the cock or valve casing, through which the gas or other fluid passes from the pipe to the fixture. The casing is preferably provided with a closed top and with a more or less conical valve-seat C, in which is seated a tapering rotary valve D, provided in its lower end with a central circular recess E, from which extend diametrically opposite radial recesses F.

G indicates an axial pin or stud within the recess E for a purpose to be made apparent.

H indicates a key-guide or cap which is forced into the lower end of the valve-seat and secured in any suitable manner. This guide has an axial aperture or flared bore I, from which extend diametrically opposite radial recesses K, and upon its upper end are formed a pair of limiting-lugs L, extending within a narrow spiral spring or split ring M, which when the parts are assembled is intermediate of the guide and valve and is designed to constantly urge the valve snugly within its seat to compensate for wear.

N indicates a key the stem of which is hollow for the reception of a pin or plunger O, provided at its extremity with an enlargement or collar P, against which bears one end

of the spiral spring Q, surrounding the plunger and bearing at its opposite end against the solid portion of the key.

R R indicate radial lugs projecting from the end of the key-stem.

The device being organized as described and in the closed position, the key is passed through the guide H until the stud G contacts with the plunger in the key. The key is now urged inward against the resistance opposed by the spring Q until the key-lugs R R are in engagement with the recesses F in the valve. The turning of the key will now cause the valve to be rotated until the port or opening through the valve is brought into coincidence with the opening through the valve-casing, at which time the lower edges of the key-lugs R R (which project below the valve) will come into contact with the stop-lugs L and will prevent further rotation of the parts. It will now be seen that the key-lugs have been moved out of coincidence with the recesses K in the guide, which makes impossible the withdrawal of the key in this the open position of the valve. The valve may now be turned back to its closed position, and as soon as the key-lugs come into apposition with the recesses K the spring Q will expel the key.

The key D may be attached to the fixture by a short chain, if desired, or it may be carried in the pocket or put in a safe place convenient for use.

It will now be readily seen that so long as the key D remains in place the gas will flow and that with the removal of the key the gas is shut off and cannot be turned on again without the deliberate act of again inserting and turning the key, thus avoiding all danger of accident from escaping gas. The use of the key is especially desirable in places where the presence of a light is dangerous, as it makes it possible to put the care of the light in the hands of a careful and competent person, without whose presence it cannot be used.

The devices herein described are also useful and are designed in part for use in connection with liquids which are valuable or which require careful handling.

What we claim is—

1. The combination with a valve-casing and valve provided with a central opening and

diametrically opposite recesses in one end, of a key-guide seated within the bottom of the casing and provided with a central opening and radial recesses, a hollow key provided 5 with external lugs and a spring-actuated pin within the key designed to eject the key from the valve in a given position of the latter, substantially as specified.

2. The combination with a valve-casing and 10 valve provided with a central recess in one end and with radial recesses extending from the central recess, of a key-guide within the bottom of the casing provided with a central opening and radial recess, a spring between 15 the key-guide and valve, a hollow key provided with external lugs and longitudinally-movable pin within the key and having an enlargement, and a spring surrounding the

pin and designed to urge it into operative relation with the valve whereby both springs 20 serve to urge the valve upon its seat when the key is inserted, substantially as specified.

3. The combination with a valve-casing and valve provided with recesses in one end, of a key-guide provided with a central opening, 25 radial recesses and with limiting-lugs upon its upper face, and a key provided with lugs designed to engage the recesses in the valve and to abut against the lugs upon the key-guide to limit the rotation of the valve, substantially as specified.

DANIEL J. MCOSKER.
OWEN F. GARVEY.
